UNITED STATES PATENT OFFICE.

ARTHUR CURRIER, OF MANCHESTER, NEW HAMPSHIRE, ASSIGNOR TO
DODGE NEEDLE COMPANY, OF MANCHESTER, NEW HAMPSHIRE.

KNITTING-MACHINE NEEDLE.

SPECIFICATION forming part of Letters Patent No. 743,152, dated November 3, 1903.

Application filed August 26, 1901. Serial No. 73,378. (No model.)

To all whom it may concern:

Be it known that I, ARTHUR CURRIER, a citizen of the United States, residing at Manchester, in the county of Hillsboro and State 5 of New Hampshire, have invented an Improvement in Knitting-Machine Needles, of which the following description, in connection with the accompanying drawings, is a specification, like numerals on the drawings representing 10 like parts.

Needles for knitting-machines are commonly made by providing the body of the needle with a slot in which the end of the latch is pivoted, a pivot-pin being passed 15 through the body of the needle and the latch for this purpose and being headed over at its ends to retain it in place. One objection to this construction is that it is very difficult to spread or head over the end of the pivot- 20 pin, so as not to leave a slight bur or roughness which will catch on the fiber of the yarn and injure the same. Various expedients have been resorted to to cure this objection, one of them being to insert the pivot-pin into a drilled 25 hole in the body of the needle, said pivot-pin passing through the usual eye in the end of the latch and being shorter than the width of the body of the needle, whereby the ends of the pivot-pin are below the surrounding surface 30 of the side walls of the needle. To hold the pivot-pin in place, the body of the needle was swaged or upset, so that portions thereof were displaced to partially close the drilled hole therein, the displaced metal overlapping 35 the ends of the pivot-pin and operating to retain it in place. This manner of securing the pivot-pin in place, however, has not been entirely successful, because it is extremely difficult to locate a pivot-pin centrally in the 40 needle-body, so that its opposite ends are supported uniformly in the body of the needle, as is necessary to make a perfect needle. Moreover, difficulty has been experienced in making the countersinks in the opposite 45 sides of the needle of uniform depth, this difficulty arising from the fact that the walls of the needle are very thin and the pivot-pin is apt to have its ends extended unequally into the body of the needle. It has also been 50 proposed to secure the pivot-pin in place by first making a comparatively deep counter-

sink in the side walls of the needle and heading over the ends of the pivot-pin into said countersink in such a way that the edges of the heads on the pivot-pin are below the surrounding surface of the side walls of the needle. This form of needle, however, is objectionable, because the making of the comparatively large countersinks in the side walls thereof materially weakens the needle 60 at the very point where the most strain comes thereon and where the needle needs to be the strongest. Moreover, experience has demonstrated that even though when the needle is first made according to this method the 65 head of the pivot-pin is carried below the side walls of the needle; yet after the needle has been in use some time the pivot invariably works loose and the thin edges of the heads of the pin will project above the surrounding surface of the side walls of the needle, thus forming a bur or roughness which will catch the fiber of the yarn. Still another way in which needles have been constructed is to provide the side walls of the 70 needles with the usual countersinks into which the ends of the pivot-pins are headed or spread, as usual. The headed ends of the pivot-pins and a portion of the surrounding side walls of the needles have then been 75 dressed off by a revolving tool to form countersinks, so that the ends of the pivot-pins are carried below the surface of the side walls of the needle. It has been found in practice, however, that a revolving tool will 80 leave a rough edge surrounding the countersink, and such rough edge is sufficient to catch and pull the fine fibers of delicate yarns, thereby unfitting a needle constructed as above described for many classes of work. 85 Another disadvantage in this form of needle is that in forming the countersinks by dressing off or removing the portion of the needle-body the said body is thereby weakened. 90

It is the object of my invention to provide a 95 novel form of knitting-machine needle which will do away with all of the disadvantages above named and which at the same time will be so constructed that there is no bur or other roughness which can engage and pull 100 the fiber of the yarn. Accordingly I provide my needle-body and latch with the usual

drilled hole, in which the usual pivot-pin of suitable length is inserted, and after the pivot-pin has been put in place it is shortened either by cutting or grinding off or hammering down 5 the ends of the pin until it is of a length substantially equal to the width of the needle-body, the ends of the pivot-pin coming substantially flush with the body. Thereafter the needle is placed between suitable dies or 10 punches, the acting faces of which are convex in shape and are of slightly greater area than the area presented at the ends of the pivot-pin, and these punches meet the outer sides of the needle, cover the ends of the pivot-pin, 15 and shorten or swell the pivot-pin in the body of the needle and in the hole in the latch thereof, the hole in the latch being enough larger than the upset pivot-pin to leave the latch free to turn on the pivot-pin. This operation of the punches compresses the material of the needle-body to form a depression in each side of the needle and at the same time shortens or compresses the ends of the 20 pivot-pin and carries the said ends below the surface of the surrounding side walls of the needle, the ends of the pivot-pin constituting 25 and lying substantially flush with or a little below the bottoms of the depressions.

The operation of shortening the pivot-pin 30 in the body of the needle operates to swell the same to thereby completely fill the hole in the body of the needle, whereby the pivot-pin is firmly held in place and at the same time the ends of the pivot are carried below the 35 rounding side walls of the needle, a feature which experience has proved is necessary in this class of devices. Moreover, by forming the depressions by compression instead of by removing a part of the metal to form usual 40 countersinks it will be seen that the full original strength of the needle-body is preserved at the point where the said body is weakest and is subjected to the most strain.

In the drawings, Figure 1 is a perspective 45 view of a knitting-machine needle embodying my invention. Figs. 2, 3, and 4 are transverse sections through the needle at the pivot-pin, said figures showing the needle in different stages of completion. Figs. 5, 6, and 7 50 are also transverse sections of the needle at the pivot-pin, showing a slightly-modified form of needle in its different stages of construction; and Fig. 8 is a side view of a portion of the completed needle.

55 The body 3 of the needle may be of any usual or suitable construction and has pivoted in a slot in the end thereof the usual latch 4.

To obtain a needle which has no roughness 60 or bur at the head of the pivot, I construct the needle as follows: The body 3 is provided with the usual hole drilled therein for the reception of the pivot-pin 5, said pivot-pin passing through the body of the needle and through 65 the hole or eye 6 in the end of the latch 4, the hole or eye 6 being somewhat larger than the hole in the body of the needle, as shown in

the drawings. After the pivot-pin, which is longer than the width of the body of the needle, is inserted through the body of the needle and the eye 6 of the latch, as shown in Fig. 2, the said pivot-pin is shortened in any suitable way until the ends thereof stand substantially flush with the side walls of the needle, as shown in Fig. 3. The pivot-pin may 70 be shortened in any suitable way, and in the form shown in Figs. 2 to 4 the same would preferably be either cut off or removed by a grinding process until the ends of the pivot 75 come flush with the side walls of the needle. Thereafter I subject the pivot-pin in the condition of Fig. 3 to the action of two suitable dies or punches 7, 8, having convex faces and being preferably slightly larger in diameter 80 than the pivot-pin. As these punches or dies 85 approach each other they act upon the ends of the pivot-pin and also upon a portion of the body of the needle immediately surrounding the ends of the pivot-pin, the said punches depressing the walls of the needle-body, as 90 at 9, and at the same time shortening and enlarging the pivot-pin 5, whereby the end portions thereof are made to completely fill the aperture or hole in the side walls of the needle 95 and the ends thereof are in position to form the bottoms of the depressions 9, as seen in Fig. 4. At the same time this shortening process of the pivot-pin enlarges the central portion thereof, as at 10, to fill the aperture or eye 6 in the latch 4, as illustrated. In this 100 modification the end portions of the pivot-pin are of substantially uniform diameter and have no heads thereon; but by my process of construction the said pivot-pin is made to fit the holes in the needle-body so tightly that 105 the said pivot-pin cannot become loosened. Furthermore, none of the metal of the needle-body is removed in making the depressions, and therefore the full strength of the said 110 body is preserved at its weakest point.

Figs. 5, 6, and 7 show a slightly different way of arriving at substantially the same result, and in this case the side walls of the needle are provided with slight countersinks 115 19, which are so small as not to appreciably affect the strength of the needle. The pivot-pin 5 of a suitable length is inserted in the body of the needle, as usual and as shown in Fig. 5, and the said pivot-pin is shortened until the ends thereof are substantially flush 120 with the side walls of the needle, as shown in Fig. 6. This shortening of the pivot-pin may be accomplished in a variety of ways; but preferably the ends of said pin are spread to form small heads 20, which fill the counter- 125 sinks 19 and come substantially flush with the side walls of the needle. Thereafter the needle is placed between suitable dies 7, 8, which, as above described, have convex spherical ends and which are slightly larger in diameter 130 than the small heads 20 on the ends of the pivot-pins. The dies form by compression the depressions 9 in the side walls of the needle, the act of making the depressions serving

to shorten the pivot lengthwise by compression and swell or bulge the same centrally thereof, as at 10, as above described. In this modification of my invention the countersinks 5 19 and the small heads 20 on the pivot-pins are carried by compression below the surrounding side walls of the needle and the ends of the pivot-pins come substantially flush with and form the bottoms of the depressions 9'.

Referring to Fig. 8, it will be seen that since the dies are circular in cross-section the depressions 9 9' will be circular, whereby the ends of the pivot-pin are concentric with 15 the said depressions and the material in the side walls of the needle adjacent the ends of the pivot-pin is uniformly compressed.

Two important and necessary features in knitting-machine-needle construction are inherent in both of the above forms. In the first place, the ends of the pivots, whether headed or not, are carried below the surrounding side walls of the needles, and this is done in such a way as to leave no bur or 20 other roughness which can catch or pull the fiber of even the most delicate yarn, and, in the second place, the formation of the depressions is not accompanied by any removing of the metal of the needle and a consequent weakening of the needle at the very 25 place where it should be the strongest.

Another advantage which I would call attention to is that by having the pivot of a length substantially equal to the width of the 30 needle-body prior to the action of the dies the pivot-pin is maintained in its central position in the body of the needle, a result which is very difficult of accomplishment where the pivot-pin before it is shortened or 35 compressed is shorter than the width of the needle-body.

I desire to state that various changes may be made in the structure of the device with-

out departing from the invention as expressed in the accompanying claims.

45

This application is a continuation of and has been filed to take the place of my former application, Serial No. 737,407, filed November 8, 1899.

Having described my invention, what I 50 claim, and desire to secure by Letters Patent, is—

1. A knitting-machine needle comprising a body having a latch mounted on a pivot-pin, the said pivot-pin and the side walls of the 55 body adjacent the ends of the pin being compressed to form depressions, the compressed ends of the pins coinciding with the bottom of the said depressions.

2. A knitting-machine needle comprising a 60 body, a latch and a pivot-pin in said body upon which said latch is loosely mounted, the side walls of the body adjacent the ends of the pins being compressed to form depressions, the ends of the pins being flush with and 65 forming a portion of the bottoms of the said depressions.

3. A knitting-machine needle comprising a body, a latch, and a pivot-pin in said body upon which said latch is loosely mounted, the 70 outer side walls of said body having that portion which surrounds and is concentric with the ends of the pivot-pin compressed to form depressions, the pivot-pin also being compressed longitudinally thereof and the ends 75 of said pin when compressed being flush with and forming a portion of the bottom of the depressions.

In testimony whereof I have signed my name to this specification in the presence of 80 two subscribing witnesses.

ARTHUR CURRIER.
